UNITED STATES PATENT OFFICE

FRANK J. BUDDE, OF ST. LOUIS, MISSOURI

ORNAMENTAL DEVICE FOR AUTOMOBILE RADIATORS

Application filed September 4, 1928. Serial No. 303,704.

This invention relates to a novel ornament for a radiator of an automobile of a type designed to be moved by the pressure of the air while the machine is running. The general object of the invention is to provide a device of this type which will oscillate in a vertical plane under variations in wind pressure.

In the preferred embodiment of the invention, I mount a miniature airplane, with or without a rotatable propeller, on one end of an arm, the other end portion of which is mounted on the radiator cap in a manner to permit of an oscillating movement of the arm as the airplane is caused to rise and fall by variations in wind pressure due to increase or decrease in the speed of the automobile carrying it. It may be stated at this point, however, that the invention is not limited to the particular object carried by the oscillating arm except to the extent that such object should be of a character to present an inclined surface to be acted on by the wind pressure to cause the object to rise. For example, an alternative object would be a bird with outstretched wings.

In the drawing:

Fig. 1 is a view in side elevation and partly in section, showing my ornamental device, the full lines showing the normal position of the parts and the dotted lines the position they assume when the automobile is traveling at such speed as to produce sufficient wind pressure to cause the object to rise; Fig. 2 is a plan view; Fig. 3 is a view in front elevation; and Fig. 4 is a sectional view taken on the line 4—4 of Fig. 1.

Referring now to the drawing the numeral 1 indicates the upper portion of the radiator of a car having the usual cylindrical upwardly projecting portion 2, provided with a cap 3. In order to secure my improved device on the radiator I provide a split ring 4 which is adapted to encircle the cylindrical portion 2 and to be firmly clamped thereon by means of a screw 5. This draws its two ends together, in the usual manner of such clamping devices. Projecting from the front end of the split ring 4, and integral therewith, is a bracket arm 4^a having a horizontal portion 6, which is apertured to have a bolt 7 pass

upwardly through it, the head of the bolt 8 engaging the under side of the bracket and the bolt being secured in position by means of a nut 9 which is screwed on the bolt and bears against the upper part of the horizontal portion 6 of the bracket. The shank 7 of the bolt constitutes a vertical post on which my improved device is directly mounted.

My improved device comprises a relatively long curved arm 10, which is reversely curved at its forward end to provide an end portion 11 which, in a general way, is substantially parallel with the main portion 10 of the arm.

The reversely bent portion 11 of the arm is provided in its end with a slot 12 (Fig. 4) which is adapted to receive and slide over the vertical post 7, said end portion, when in position, resting on the nut 9. That part of the arm 10 immediately above the slot 12 is provided with a circular opening 13 (Figs. 1 and 2) through which the upper portion of the post 7 projects. The aperture 13 is somewhat larger than the post so as to permit some degree of angular movement of the arm 10 relative to said post. Above and below the arm 10 pins 14 and 15 are secured in the post 7, to project from opposite sides thereof, the upper pin, 14, confining the arm 10 on the post and the pin 15 limiting the downward movement of said arm. The pin 14 serves as a pivot for the arm in its upward movement and the pin 15 as a pivot for the arm in its downward movement, in both of which movements the slot 12 slides over the post 7. The numeral 16 indicates an ornamental object which I pivotally mount on the end of arm 10. In the present instance this object is shown in the form of a miniature airplane having a fuselage 17, wings 18 and propeller 19 which, if preferred, may be mounted to rotate on the end of the fuselage. On the under side of fuselage 17 I provide two parallel downwardly projecting bracket members 20 (Figs. 1 and 3) which embrace the upper end of the arm 10. Said arm at this point, is provided on either side with downwardly extending flange members 21. The bracket members 20 and the flanges 21 are correspondingly apertured to receive a pivot pin 22, about which the airplane is free

to turn through a limited arc of movement in a vertical plane. To prevent the rear part, or tail portion, of the airplane from making a downward turn, in the manner of a tail spin, I provide the end of the arm 10 with a curved portion 23 extending rearwardly beyond the pivot 22 and which is so located as to engage the under side of the fuselage of the airplane when its forward end has been turned upward as far as desired. This position of the parts is shown by the dotted lines in Fig. 1.

In order to properly balance the device so as to permit of the oscillating movement on the post 7 described, I mount in the curved portion of the arm 10, forwardly of post 7, a counterweight 24 (Figs. 1 and 4) and to give this part of the device an ornamental appearance, I preferably secure on this curved front end of the arm 10 some character of ornament, such as a conventional leaf, shield, or the like, 25. If desired the curved portion of the arm 10 itself may be finished to present such ornamental figure 25.

It will be understood that the invention is not limited to the precise details of construction shown nor to the position or arrangement thereof except to the extent that such features are involved in the claims. For example, by preference, the arm 10 projects rearwardly over the hood of the car and is freely rotatable about the post 7 and it can therefore be turned to one side, or to a position where the airplane projects outwardly in front of the car, when it is desired to lift the sides of the hood. But it will be apparent that the invention could be readily arranged so that the arm 10 with the object 16 suitably positioned thereon could project forwardly of the car.

I claim:—

1. A device of the character described comprising, in combination with the radiator of an automobile, a support secured on the top of the radiator having a vertical post, an arm having one end reversely curved and provided with a slot receiving said post to permit said end to rest on said support, the main body of the arm having an aperture aligning with said slot and receiving the upper end of said post, members mounted on said post above and below said arm in the zone of said aperture, and an ornamental object mounted on the free end of said arm and presenting an inclined surface to the air in the forward movement of the automobile to cause the free end of said arm to raise under air pressure.

2. A device of the character described comprising a vertical post, an arm pivotally mounted on the upper end thereof and having an adjacent end portion slidably engaging the lower portion of said post, and an ornamental object secured at the opposite free end of said arm and presenting an upwardly inclined surface to cause the object

to raise the free end of the arm under air pressure.

3. A device of the character described comprising a vertical post mounted on the radiator of an automobile, an arm pivotally mounted toward one of its ends on the upper end of said post and projecting rearwardly therefrom, said arm having a forward curved extension provided near said end with a slot slidably engaging the lower end portion of said post, whereby to permit said arm to have an oscillating movement in a vertical plane on said post, and a miniature aeroplane secured on the free end of said arm and having its wings upwardly inclined in the direction of movement of the car to cause the aeroplane to raise the free end of the arm under air pressure.

4. A device of the character described comprising, in combination with the radiator of an automobile, a vertical post secured on the top of the radiator, an arm pivotally mounted toward one of its ends on the upper end of said post and projecting outwardly therefrom, said arm having an end portion adjacent said pivot slidably engaging the lower portion of said post, whereby to permit a restricted oscillating movement of the arm on said post in a vertical plane, a miniature aeroplane pivotally secured on said arm toward the opposite free end thereof and having its wings presenting an upwardly inclined surface to the air in the forward movement of the automobile, and means on said arm for limiting the pivotal movement of said aeroplane in one direction.

In testimony whereof, I have hereunto set my hand.

FRANK J. BUDDE.
